<img alt="Technical drawing of a mechanical assembly, labeled 'Fig. 1', showing a complex arrangement of gears, shafts, and bearings. The drawing is a cross-sectional view with various parts labeled with numbers such as 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 669, 670, 671, 672, 673, 674, 675, 676, 677, 678, 679, 680, 681, 682, 683, 684, 685, 686, 687, 688, 689, 690, 691, 692, 693, 694, 695, 696, 697, 698, 699, 700, 701, 702, 703, 704, 705, 706, 707, 708, 709, 710, 711, 712, 713, 714, 715, 716, 717, 718, 719, 720, 721, 722, 723, 724, 725, 726, 727, 728, 729, 730, 731, 732, 733, 734, 735, 736, 737, 738, 739, 740, 741, 742, 743, 744, 745, 746, 747, 748, 749, 750, 751, 752, 753, 754, 755, 756, 757, 758, 759, 760, 761, 762, 763, 764, 765, 766, 767, 768, 769, 769, 770, 771, 772, 773, 774, 775, 776, 777, 778, 779, 780, 781, 782, 783, 784, 785, 786, 787, 788, 789, 790, 791, 792, 793, 794, 795, 796, 797, 798, 799, 800, 801, 802, 803, 804, 805, 806, 807, 808, 809, 8010, 8011, 8012, 8013, 8014, 8015, 8016, 8017, 8018, 8019, 8020, 8021, 8022, 8023, 8024, 8025, 8026, 8027, 8028, 8029, 8030, REENFORCING CINEMATOGRAPH FILM

Niels Pedersen, Marion, Pa., assignor to Armoured
Films Limited, London, England, a corporation
of Great Britain

Application December 23, 1930
Serial No. 504,302

15 Claims. (Cl. 1—2)

This invention relates to the art of armoring motion picture film or similar strip and has for an object the provision of improved apparatus for and process of armoring, and the improved article produced thereby.

Numerous suggestions have been advanced for armoring motion picture film to make it last longer, it being a matter of grave concern that unarmored strip is easily torn or mutilated by the 5 sprocket teeth of picture projecting apparatus. In spite of the attention given the problem in the past, armored film has not yet come into general use. Film shrinkage is the major evil working against the successful application and use of 10 15 armoring on film. Since the armor—which most desirably is metal—does not have shrinkage characteristics corresponding to those of the film its employment presents serious difficulties.

Film strip is made in a certain standard size 20 with all sprocket holes a given standard distance apart. It is subject to shrinkage with age and also with atmospheric changes. Its major shrinkage, however, occurs during the developing processes. Thereafter, if the film is kept according to usual practice, in sealed containers except for the relatively short periods of exhibition, it will undergo relatively little additional shrinkage. The developing processes themselves 25 do not render armoring either necessary or 30 desirable.

It, therefore, appears that if the armor is applied subsequent to the developing processes it well may be made the same length as the film at the time of application with good expectations 35 that no serious buckling will occur during the remaining useful life of the film—which is usually short but active. This has apparently not been realized before for the armor has either been made standard size, which caused the shrunken 40 film to stretch at the edges and buckle in the center or the film has been armored in anticipation of future shrinkage, which caused it to buckle at the time of assembly.

According to the present invention the armor 45 strips are made to correspond as nearly as possible to the actual length of the film strip at the time of assembly. In order to accomplish this, means have been provided for first accurately and quickly determining the actual length of the 50 film; and next, means have been provided for applying the armor in the desired manner. The armor-applying means, it will be found, however, is not limited to the application of armor in the preferred manner but is capable of applying it 55 in other ways. In any event, the machine may

be quickly adjusted for various methods of application and in each case will indicate accurately what the setting is.

In order to furnish a better understanding of the nature and objects of the invention it will be described in connection with an illustrative embodiment of apparatus, reference being made during the description to the accompanying drawings, in which:

Fig. 1 is a front elevation of the entire apparatus;

Fig. 2 is a right end elevation, reference being made to Fig. 1;

Fig. 3 is a top plan view;

Fig. 4 is a left end elevation;

Fig. 5 is a vertical section taken on the line 5—5 of Fig. 1;

Fig. 6 is a partial vertical section taken approximately on the line 6—6 of Fig. 7, showing brake and clutch mechanism of one of the 75 presses;

Fig. 7 is a partial plan view of the same;

Fig. 8 is a vertical section of the strip feeding or picker mechanism;

Fig. 9 is a front elevation of the same;

Fig. 10 is a horizontal section taken on the line 10—10 of Fig. 9;

Fig. 11 is a plan view of the armor punching mechanism taken on the line 11—11 of Fig. 12;

Fig. 12 is a vertical section taken on the line 12—12 of Fig. 11;

Fig. 13 is a plan view looking upward on the line 13—13 of Fig. 12;

Fig. 14 is a view similar to Fig. 12 but showing the parts in a different position;

Fig. 15 is a transverse section taken on the line 15—15 of Fig. 12;

Fig. 16 is a right end elevation, reference being made to Fig. 11;

Fig. 17 is a vertical section taken on the line 17—17 of Fig. 12;

Fig. 18 is a plan view of the film strip punching mechanism, the view being taken on the line 18—18 of Fig. 19;

Fig. 19 is a vertical section taken on the line 19—19 of Fig. 18;

Fig. 20 is a vertical section taken on the line 20—20 of Fig. 21, showing the assembling mechanism;

Fig. 21 is a vertical section taken on the line 21—21 of Fig. 20;

Fig. 22 is a view similar to Fig. 20 but showing the parts in a different position;

Fig. 23 is a plan view taken on the line 23—23 of Fig. 20;

Fig. 24 is a diagrammatic view in elevation illustrating the steps in the operation;

Fig. 25 is a corresponding plan view;

Fig. 26 is a plan view of a measuring gage; and

5 Fig. 27 is a similar view with the parts in a different position.

First, the shrinkage condition of the roll of film to be armored is determined. In order that the shrinkage may be accurately determined the 10 distance between a considerable number of sprocket holes, say one hundred as in the present case, is measured. The apparatus shown in Figs. 26 and 27 may conveniently be used for this purpose.

15 The measuring apparatus comprises a base 20 which may be placed upon a bench or other convenient support. A fixed pin 21 is secured near one corner of the base to take into one hole of the film. A similar pin 22 is secured to a 20 pointer 23 pivoted at one end by a journal pin 24 to the base. The free end of the pointer moves over a fixed scale 25 which reads directly in percentage of shrinkage. The scale is calibrated from 0% to 1.5% shrinkage, this being 25 sufficient to cover the permissible shrinkage range.

For consistent and comparable results the movable pin 22 must enter the same numbered hole (the 100th here) each time. Since the range of 30 movement of the pin 22 is greater than the distance between adjacent sprocket holes (the scale distance 0% to 1% of course, representing one space in the hundred taken) it might enter either the 101st, 100th or 99th, depending upon the 35 shrinkage condition of the film. Herein means are provided for precluding its entry into any other than the 100th hole.

The pin 22 is mounted in a block 26 slidable in an undercut retaining groove 27 extending 40 to the fixed pin 21. There are three (more if desired) other similar blocks 26 slidable in the groove. They carry pins 28, 29, 30 like the pins 21 and 22 which fit snugly between the front and back edges of the sprocket holes of the film. When 45 the pin 21 enters the zero hole of the strip the pin 28 on the first block will enter the 25th hole. This is the first hole it can enter. It cannot enter a subsequent one because the shrinkage will not amount to one hole space in twenty five 50 holes. Likewise the pin 29 will enter the 50th hole because the variation in distance between the twenty fifth and fiftieth holes will now amount to one space. For the same reason the pin 30 will enter the 75th hole and the pin 22 will 55 enter the 100th hole—and no other.

When all of the pins 21, 28, 29, 30, 22 are in their proper holes the blocks will be substantially in end contact if the maximum shrinkage 60 provided for by the scale has occurred but will be spaced apart for any other degree of shrinkage and will be the maximum distance apart if the shrinkage is zero.

Usually the roll of film is measured at a number of places to see if the shrinkage is uniform. If it varies but by only a small amount an average may be struck and the armor strip applied according to this average. Or if the variation is great a record may be made of it and the 70 armor strip applied in different lengths at different places to correspond.

Knowing the exact shrinkage condition of the film the armoring machine is set to operate accordingly. The controls are so few and simple 75 that this setting may be readily effected. These

controls will be considered hereinafter in connection with the mechanisms which they affect.

The armoring machine as here embodied comprises three main positions or operation stations. At station #1 the metal armor strips A1 and A2 80 are punched to form sprocket holes 35 and rivet protuberances 36 therein at predetermined adjustable distances therealong; at station #2 the film strip is punched to form rivet holes 37 there- 85 in, the sprocket holes 38 having already been punched; and at station #3 the film and armor strips are laid together, the rivet protuberances are pierced to form hollow rivets positioned in the rivet holes of the film, the rivet burrs are turned and the burrs are subsequently flattened 90 upon the film strip.

Supporting frame

The mechanisms at all of the stations are run at the same speed, preferably in synchronism, and 95 are all supported upon the same table 40. The table is carried upon legs 41 connected at the bottom by longitudinal inverted channel beams 42. Three standards 43 at the three stations are bolted to the table by cap studs 44. 100

Driving mechanism

A motor M is bolted upon the rear channel beams 42. The shaft 50 thereof drives speed reduction gearing mounted within a gear casing 105 51 bolted upon the front channel beam 42. The drive emerges from the gear casing through the protruding shaft 52. At one end (the left, Fig. 1) the shaft 52 is provided with a small or low speed pulley 53 and at its other end with a large 110 or high speed pulley 54. The pulley 53 through a belt 55 drives a low speed clutch pulley 56 rotatably mounted upon the clutch shaft 57. The clutch shaft is rotatably mounted in bearings 58 secured beneath the table. The pulley 54 through 115 a belt 61 drives a high speed clutch pulley 62 also rotatably mounted on the shaft 57.

Slidably splined on the clutch shaft 57 near the low speed pulley 56 is a clutch operating collar 63. A yoke 64 carried by a clutch lever 65 120 operates in an annular groove on the collar 63. The lever 65 is pivoted at its upper end by a pin 66 to the lower side of the table.

Likewise there is slidably splined on the clutch 125 shaft 57 near the high speed pulley 62 a clutch operating collar 67. A yoke 68 carried by a clutch lever 69 operates in an annular groove on the collar 67. The lever 69 is pivoted at its upper end by a pin 70 to the lower side of the table. 130

The clutch levers 65 and 69 are connected together for simultaneous operation by a link 73. The link is pivoted to the levers by pins 74, 75. The levers are normally urged toward the right by a coil spring 76 to keep the low speed clutch 135 engaged but may be moved toward the left to disengage the low speed clutch and engage the high speed clutch by a clutch shift pedal 77 and connecting linkage generally designated by the reference numeral 78. The foot pedal is pivoted at its rear end and when pressed down at its front end for high speed is held down by the end of a bell crank latch 79. The latch is biased into pedal-engaging position by a spring 80.

The clutch shaft 57 through a pulley 81 fast 145 thereon, a belt 82, and a weighted jack shaft pulley 83 drives a jack shaft 84 rotatable in bearings 85 mounted on one of the pair of strengthening ribs of each of the standards 43. The shaft 84 drives the mechanism at all of the three sta- 150

tions and thus completely coordinates the several operations.

At each station the shaft 84 is provided with a gear 86 fast thereon, which gears mesh with 5 and drive similar gears 87 loose on each of three press shafts 88, at stations #1, #2 and #3 respectively. The shafts 88 are mounted in spaced bearings 91 and 92 on the top and at the front of the pedestals.

10 *Clutch-brake mechanism*

Means are provided for giving separate control for the several presses, or if desired, collective control independent of the jack shaft 84. Stated 15 in terms of the specific mechanism illustrated, each shaft 88 is furnished with a clutch 95 and a brake 96 for controlling its rotation independently of the common drive for all the shafts 88.

The clutches may be any well known type— 20 preferably the dental type—in order that the parts may be engaged at the same point each time, whereby the several presses may be kept in step with each other. The particular clutch illustrated in Figs. 6 and 7 comprises the gear 87, 25 already referred to, which is loosely mounted to rotate freely on the shaft 88, the gear being held on the shaft by a collar 99. A flanged sleeve 100 is pinned to the shaft 88 and this supports a cam ring 101 having some circumferential movement thereon and a brake drum 102 which is pinned to the shaft with the sleeve 100. An axially movable dental clutch pin 103 is normally biased 30 toward a radial slot 104 formed on the hub of the gear 87. The ring 101 is normally urged to 35 turn circumferentially with respect to the pin 103 to allow the pin to enter the slot 104.

When the lug 105 formed on the cam ring 101 is engaged by a radially movable clutch plunger 106 the cam ring is held and its cam surface 107 40 by engagement with the under surface of a head projection 108 formed on the clutch pin 103 withdraws the pin from the slot 104.

Simultaneously with this clutch disengaging action the split brake bands 110 are released 45 from the spreading action of the cam 111 and close under the action of the spring 112 to grip the brake drum 102 and stop the movement of the press. The brake bands are mounted upon a pivot pin 113 carried by a bracket 114.

50 In operation, the plunger 106 is pulled out to permit the clutch to be engaged at the same time that the brake is released by the spreading action of the cam 111. The plunger is actuated by a bell-crank lever 117 and the brake cam is actuated by a cam arm 118.

The bell crank lever 117 of the clutch and the cam arm 118 of the brake are connected by rods 119, 120 respectively (Fig. 2) to a foot pedal 121 pivoted at its rear end upon a pin 122. There are 55 (Fig. 1) three of these foot pedals, one for each press, permitting any one of the presses to be operated while the others are idle.

Means are provided for causing all of the presses to be operated simultaneously. These 60 means comprise the gang foot pedal 125 operating a gang shaft 126 which is provided with arms 127 and stop adjusting bolts 128 positioned above each of the individual press pedals 121. When the gang pedal 125 is depressed it depresses all of the pedals 121 together to disengage all of the press brakes and to allow all of the press clutches to be engaged.

A spring biased bell-crank latch 129 engages the pedal 125 when depressed to hold it down.

65 Means are provided for quickly stopping the

machine. Normally when the machine is operating the high-speed foot pedal 77 is held down by the latch 79 and the press gang pedal 125 is held down by the latch 129. The horizontal arms of the latches 79 and 129 overlap and beneath them there is positioned a trip finger 132 provided on the trip rod 133. The trip rod is guided near its lower end in a hole formed in the front channel beam 42 and at its upper end is attached to the handle 134 extending to the front of the machine for ready access to the machine operator. When the handle is pulled up both latches 79 and 129 are released, throwing the machine back into low gear. By the same action all presses are unclutched from the driving means 80 and their brakes applied to stop them quickly.

75 *The presses in general*

All of the presses in this much are alike: they include (referring to both Figs. 1 and 5) an eccentric 140 on the press shaft 88 operating in a bearing 141 adjustably secured to the upper end of an eccentric rod 142. At its lower end the eccentric rod is provided with a knuckle ball 143 fitting within a spherical socket formed conjointly in the thrust block 144 and the retaining ring 145. The block and retaining ring connect the eccentric rod to a cross-head 146 whose slide 147 reciprocates along vertical guides 148 formed on the front of the standard 43. The slides are retained by guide plates 149 held by cap bolts 150. The slide is tightened and located in the guide by V-shaped gibbs (not shown) on either side which are adjusted (Fig. 1) by set screws 151.

The cross-head on its under side is machined 95 to a plane surface 155 parallel to the top surface of the table. Secured beneath the cross-head is a punch holder 156, the same having a plane top surface 157 facing the lower surface 155 of the cross-head and being removably held thereto by cap bolts 158. The punch holders cooperate with die holders 159, there being a plurality (four here) of guide studs 160 secured to one of the holders and corresponding guide apertures 161 formed on the other of the holders. 100 The die holder is provided with a plane surface 162 on its lower side which is parallel to the surfaces 155 and 157 and which faces the top surface of the table. The die holder is clamped to the table by cap bolts 163.

105 It is thus seen that the punch holder and die holder are formed as a removable unit which is quickly connected to and disconnected from the cross-head and table. Also that the punches may be readily ground to an even length by 110 placing the punch holder upside down upon the finished surface of a grinding machine seat and grinding off the ends of the punches held thereby along a plane parallel to the surface 157 of the holder.

115 *Strip reels and guides*

120 Referring to Figs. 1 and 2 the armor strips A1, A2 for reenforcing the two sides of the film strip are taken from reels 166, 167 supported on axles 168 mounted upon a bracket 169 secured to the right hand end of the table. The reels are braked lightly to check the feed-off of strip by spring friction devices 170. The strips are directed to the punch at station #1, the strip from reel 166 travelling along the front and the strip from reel 167 travelling along the back.

125 From station #1 the strips travel to station #3, passing beneath the table at station #2 through the crossed tubes 171, 172. During this travel the strips are turned upside down and front for rear

for a purpose which will hereinafter be made apparent.

The film strip F is taken from the reel 175 carried on the shaft 176 mounted on the bracket 5 177 secured to the top of the standard 43 at station #1. The pay out of strip is retarded by a thong 178 passed over the shaft, the thong being tensioned by a weight 179. From the reel the film strip travels between the ends of the spaced 10 press shafts through a flat tube 180 supported on the standard by brackets 181, 182. Thence the film strip passes beneath a roller 183 to the punch at station #2.

In normal operation loops are formed both in 15 the film and armor strips between their punching stations and the assembling station. This is indicated in Fig. 1.

Strip feeding mechanism

20 At each station means are provided for feeding the strip to the operating mechanism. As shown in Fig. 1 the strip feeding devices are designated by the numeral 190. Each is located to the left or outgoing side of its corresponding station and 25 each is driven by a vertical shaft 191 connected by bevel gears 192, 193 to press shaft 88. The shafts 191 are rotatably mounted at their upper ends in bearings 194 secured to the standards in any approved manner. Near their lower ends 30 the shafts 191 are provided with flexible couplings 195. Referring to Fig. 4, the lower ends of the shafts 191 below the flexible couplings 195 are rotatably mounted in the bearings 196 and carry bevel gears 197 driving similar bevel gears 35 198 fast on picker cam shafts 199.

The feeding mechanism is shown in Figs. 8, 9 and 10. It comprises a frame 202 which is bolted or otherwise secured to the top of the table. The cam shaft 199 carries a cam 203 which operates 40 two cam rollers 204 and 205 to give picker pins 206 an orbital movement. That is, as shown in Fig. 8, the pins 206 on each side of the film rise upward when they are in their rearward position and enter holes of the parallel lines of sprocket 45 holes in the strip (or strips), then move forward (to the left) while raised to feed the strip, then drop down and return to rearward position while so lowered.

The picker pins 206 are adjustably held by a 50 clamp 207 and screws 208 to a cross bar 209 secured to the outer ends of parallel picker arms 210. The cam roller 204 is carried on a cross shaft 211 secured between the picker arms. It determines the vertical travel of the picker pins. 55 The arms 210 are pivoted to the upper end of a cam lever 212 pivoted at its lower end upon a journal 213. The arms 210 are urged downward toward the cam by a spring 214 and the lever 212 is urged to the right toward the cam by a spring 60 215.

The picker pins enter elongated holes 220 formed in the cover plate 221 of the picker frame and corresponding holes 222 formed in a strip retaining plate 223.

65 Means are provided for adjusting the location of the travel orbit of the picker pins. The length of the picker pin movement may remain constant, the length being dependent solely upon the contour of the cam 203, but inasmuch as the picker pins are located some twenty-five or thirty sprocket hole spaces from the punches at the several stations and since the strips will vary in length between the distant holes within this span it is necessary to change the location of the 70 picker pin orbit. This will permit the picker to

stop the strip in approximately correct position for the punches, means being there provided, as will be hereinafter explained, for obtaining absolute and final positioning of the strip prior to punching.

80 The orbit position adjusting means comprises an eccentric 224 formed on an eccentric shaft 225. The eccentric supports the cam roller 205 and the shaft 225 is rotatably mounted in bearing plates 226 attached to opposite sides of the cam lever 212. At one side of the lever 212 the shaft 225 bears a worm gear 227 meshing with a worm 85 228 fast on a thumb screw 229 rotatably mounted in a bearing 230 secured to the lever 212.

85 On its front end the eccentric shaft 225 is provided with a scale pointer 233 cooperating with a fixed arcuate scale 234. The scale is calibrated in percentum of shrinkage so as to read directly in conformity with the other adjusting instrumentalities of the apparatus and with the measured 90 percentage of shrinkage of the film.

95 The pointer has a slight movement relative to the scale but this is so small as to be negligible in the reading. Moreover, the adjustment is normally made when the machine is stopped and it 100 stops always with the press shafts and related parts in about the same positions, so the relative movement between scale and pointer may be neglected in the setting.

105 Means is provided for preventing backward movement of the strips. As shown in Fig. 8, this comprises a plunger pawl 235 provided with a bevelled foot 236 adapted to enter the sprocket holes of the strip. The pawl operates in a guide barrel 237 riveted to the plate 223. A spring 238 110 presses the pawl downward, being engaged between a shoulder on the pawl and a hollow nut 239 screwed into the barrel. The head 240 of the plunger pawl is provided with a lift lug 242 adapted to rest in a corresponding recess in the 115 nut 239 when the pawl is lowered into operative position and to ride upon the upper edge of the nut when the pawl is raised into inoperative position. There are two pawls, one for either series 120 of sprocket holes.

125 The position of the pawls is adjusted by a thumb screw 245 rotatable in a fixed bearing 246, which is threaded into a split clamp nut 247 secured to the slide plate 223 upon which the pawls are mounted. The position of the pawls is made 130 to correspond to the adjusted positions of the picker operating mechanism, a scale and indicator being provided if desired so the setting may be accurately made when the other settings for the machine are made.

Armor strip preparation at station #1

In Figs. 11 to 17 inclusive the press operated mechanism at station #1 is shown. At this station the armor strips (usually of copper) for the 135 two side edges of the film strip are punched to form sprocket holes and rivet-forming protuberances. Since the sprocket holes of the armor strip are to bear a certain relationship to the sprocket holes of the film strip, means are provided at this station for adjusting the spacing at which the holes are punched. Also since the armor strip initially has no sprocket holes or other elements by which it may be fed, special means are provided at this station for feeding the strip 140 until a sufficient length has been perforated to allow it to begin feeding in the usual way.

145 The tools employed at this station comprise a pair of positioning pins 250, a pair of sprocket hole punches 251 and two pairs (or more if re- 150

quired, depending on the number of rivets per sprocket space desired) of rivet protuberance punches 252. Die blocks 253 are provided with corresponding holes 254, 255, 256 for the positioning pins, sprocket hole punches and rivet forming punches respectively.

The positioning pins (Fig. 14) are mounted in a block 257 secured by screws 258 to an adjusting slide block 259. The holes 254 into which the positioning pins enter are made oversize to permit of longitudinal (in the length of the strips) adjustment of the positioning pins. The positioning pins are considerably longer than the punches so as to locate the strips properly and allow time for them to be clamped in position before the punches function.

The sprocket hole punches 251 have a tight frictional fit in bores 262 formed in an anchor block 263. Screws 264 retain the block 263 beneath the punch holder 156. An adjusting screw 265 and a locking screw 266 hold the punches 251 against backward movement. After adjustment the punches may be ground off at their ends along a common plane in the manner heretofore described.

The rivet punches 252 are mounted in a block 267 secured by screws 268 to the anchor block 263.

The die holder 159 is surmounted by a die block rest 270 secured thereto by cap screws 271. Upon the top at either side of the rest 270 there is secured one of the die blocks 253, the blocks being retained by cap screws 272. Accurate positioning of the die blocks upon the rest is secured by dowel pins 273 entered into matched holes in the block and rest. The hole 256 in the die block guides a backing pin 274 pressed upward by a spring 275 disposed in a counterbore of the hole 256 into cooperating relation with the rivet punch 252. The pin 274 is made concave on its upper end to receive the convex end of the punch to form the concavo-convex protuberances on the armor strip. The backing pin is provided with a head preventing its being moved too far upward.

After the protuberances have been formed on the armor strip they must be accommodated so they will not interfere with the further movement of the strips. To this end each die block is provided with a recess 276 located one space removed from the rivet punch for receiving the protuberance. Beyond the hole 254 for the positioning pin 250 each die block is provided with a groove to receive the protuberances.

Means are provided for holding the armor strips securely in proper position for the punching operation. The strips are guided laterally and retained close to the upper surface of the die block by armor guide plates 280 secured to the die blocks by holding screws 281. The screws fit in oversized holes formed in the plates to permit lateral adjustment, this adjustment being accomplished by set screws 282. As shown in Fig. 15 the plates 280 are provided with longitudinal guide grooves 283 taking the armor strips. In Figs. 11, 15 and 17 the armor strips A1 and A2 are shown in position in the guide grooves.

At the center the guide plates are cut out to expose the strips from above, the guide grooves 283, however, being continued though widened out by the connecting straps of metal 284, 285. Fitting into the open central part of the guide plates (Figs. 12, 17) is a clamp plate 286 mounted on guide studs 287 pressed downwardly by springs 288 at their upper ends. Shortly after the positioning pins 250 enter the sprocket holes

in the armor strips the clamp plate 286 is brought down upon the strips to hold them in place while the punches 251, 252 operate on them. As the punches withdraw the clamp plate continues to hold down the strips for a time to cause the punches to be withdrawn from the strips. Thereafter the clamp plate is also withdrawn.

The clamp plate is provided with apertures accommodating the punches and positioning pins, the latter being made oversize to permit adjustment of the pins.

Means are provided for adjusting the length of the spaces at which the punchings are made in the armor strips. It will be recalled that the strips are drawn forward by the picker. This pulls the strips to within a slight distance of the position they should occupy for punching. The final delicate adjustment of position is secured by the positioning pins working against the edges of the sprocket holes which have just been punched. The spacing, therefore, may be varied by varying the distance between the positioning fingers and the sprocket hole punches. The space between the sprocket hole punches and the rivet protuberance punches is not varied, which means that the protuberance will always be a fixed distance behind the rear edge of the preceding sprocket hole but will be a varying distance in front of the leading edge of the next succeeding sprocket hole. This will be found to be of importance for simplifying the mechanism at the film punching position, station #2.

The adjustment of the positioning pins is effected by adjusting the slide block 259 to which they are secured. As shown in Fig. 15 the slide block 259 is mounted in guides 291 secured by cap screws 292 beneath the punch holder 156. A gib 293 and set screws 294 serve to tighten the block in its guides in any adjusted position.

The block 259 is constantly urged to the right (Fig. 13) by coil springs 295 acting against the bottoms of sockets formed in the end of the block and an abutment 296 secured by cap screws 297 to the outer end of the punch holder 156. The block 259 is urged to the left by a conical surface 298 of an adjusting screw 299 acting against the end of a projection 300 formed on the end of the block 259. The adjusting screw is threaded into the anchor block 263 and at its outer end is provided with a thumb turn 301 and a scale 302. The scale is calibrated in percentage of sprocket space length the same as the measuring gage and the strip feeding devices so that the turn of the screw by one space on its scale will accurately space the positioning pins by one space as the film strip is measured by the gage.

Strip starting mechanism

Until enough of the armor strips has been punched to extend to the strip feeding mechanism at station #1 it is necessary to feed the strip by other means. One embodiment of means for effecting this is shown in Figures 11, 12, 14, 16 and 17. As shown in Fig. 12, a lower strip moving roll 305 is mounted on arms 306 pivoted upon a journal 307. The journal is mounted upon brackets 308 secured by cap screws 309 to the die holder 159. Upon the same journal are pivoted arms 310 carrying upper rolls 311 at their free ends, the rolls being rotatable on headed studs 312.

The shaft 313 (Fig. 11) of the lower roll extends toward the front of the machine where a hand knob 314 is provided for turning the roll and feeding the strips when the upper rolls are

pressed thereagainst. A detent collar 315 secured on the shaft 313 has a series of sockets formed on one face thereof cooperating with a spring pressed ball detent 317 carried in one of the arms 306. The turning of the collar by the distance of one socket space feeds the strips one sprocket space.

As shown in Fig. 14 the upper rolls are constantly urged down against the lower roll by springs 318. The lower roll likewise is urged downwardly by coil springs 319. The downward movement of the lower roll is limited by a stud 320 against which the arm 306 stops. The stop stud 320 may be adjusted as to height and when so adjusted may be so held by a lock nut 321.

Means are provided for releasing the strips from the rolls while the strips are being operated upon. This is desirable to avoid tearing the strips which are relatively weak as compared to the strength of the machine. The means here shown comprise cams 325 secured to a cam shaft 326 mounted in bearings in the lower arms 306. When the shaft 326 is rotated either by the hand turn 327 at its front end or by the striker arm 328 at its rear end it cams the upper rolls upward clear of the lower roll. In this position the parts may be locked—not being needed except at the start of operations—by a latch 329 engaging a notch 330 in the hub of the arm 328. The latch is normally held clear of the notch by a spring or other convenient means but when engaged with the notch is retained therein until disengaged by hand. The striker arm is operated to separate the rolls upon each downward movement of the press by a striker stud 331 threaded into the punch retainer 156. The stud may be held in various adjusted positions by a lock nut 332.

Backlash take-up

The punching operation at station #1 is a delicate one. The downward movement of the rivet protuberance punch must always be substantially the same or the protuberance will vary in size and height. If this happens the subsequent assembling operations may be unfavorably affected. This condition must be maintained even if the eccentric bearing becomes too large, by reason of wear or otherwise, for the press eccentric. The press crosshead and the punches must be positively forced down by the eccentric acting against the lower side of its bearing. When this is the case the press eccentric rod 142 can be adjusted to cause the punches to descend to exactly the same limit of travel each time.

The way this is accomplished here is by imposing resistance to the downward movement of the crosshead carrying the punches. The reason for requiring this is that the resistance offered the punches by the strips may be so small that the cross-head might descend by gravity with the upper surface of the eccentric bearing resting on the eccentric. The means for accomplishing this, as shown in Fig. 14, comprises backlash plungers 333 rigidly secured at their upper ends in the punch holder 156 and at their lower ends being guided in bores 334 formed in the die holder 159. Springs 335 sufficiently strong to support the weight of the crosshead and associated parts are disposed below the lower ends of the plungers 333. They are removable from beneath the table.

Film strip preparation at station #2

At station #2 the film strip is punched to form rivet holes therein, the strip being already

punched for the sprocket holes. The mechanism for accomplishing this is shown in Figs. 18 and 19. Here the punch holder 156 has secured thereto by dowels 340 and cap screws 341 an anchor block 342. To the lower side of this block are attached positioning pin blocks 343, cap screws 344 being employed for the attachment. The positioning pins 345 are here formed integral with the blocks 343.

Rivet hole forming punches 347 are secured in V-shaped seats formed partly in the end of the anchor block and partly in the clamp blocks 348. There are three blocks, the center one clamping two punches and the end ones each clamping one punch. The clamp blocks are held by cap bolts 349. After being clamped the punches may all be ground off on the ends along a common plane in the manner previously described.

A die rest 352 is secured to the die holder 159 by cap screws 353. A die anchor block 354 is secured to the die rest by dowels 355 and cap screws 356. Die blocks 357 are secured to the die rest 352 by cap bolts 358, the die blocks being set into openings formed in the anchor blocks 354. The dies are provided with holes 359 for the positioning pins and punch holes 360 for the punches.

Film strip retaining plates 363 are secured to the anchor block 354 by cap screws 364.

Here, just as at the armor piercing punches at station #1 the punch holes are located at a constant distance from the rear edge of the preceding sprocket hole. The rivet protuberances and rivet holes will therefore match accurately when the strips are assembled at station #3.

Assembling mechanism at station #3

At this station the armor strips and film strip are placed face to face with the protuberances of the armor strips entered in the corresponding holes of the film strip and with the sprocket holes coinciding. The rivet protuberances are pierced to form a tubular rivet, the wall of which protrudes through the film strip. Then the rivet is turned; and finally it is pressed flat. This mechanism is shown in Figs. 20 to 23 inclusive.

As mentioned above the armor strips are turned upside down as they arrive at the assembling stations. There are several reasons for doing this. One reason is that the film strip is more accurately held on the armor strips when its rivet holes overlie the rivet protuberances than would be possible if the rivet holes were disposed below the protuberances; another reason is that the burrs of the pierced rivets will not drag on the guide surfaces when turned upward, but rather a smooth strip surface rests upon the guide surfaces; and another reason is that most of the operating tools are actuated from above rather than from below when the protuberances are turned upward, a matter of considerable moment from the operating standpoint.

Since the armor strips are turned upside down they must be changed from front to back and vice versa because they were punched at station #1 by reference to a longitudinal center line—or perhaps it would be more accurate to say, by reference to the side edges of the film strip with which their side edges are to correspond—in order that they will accurately fit the film strip.

Coming now to a consideration of the exemplary mechanism shown at station #3, the punch holder 156 has secured thereto by cap bolts 367, a punch anchor block 368. Secured beneath the anchor block is a punch block 369, cap screws 370 being employed to effect the attachment.

Operation

The punch block 369 supports the positioning pins 371 and rivet turning punches 372.

An upper strip holding plate 375 is rigidly held on the lower ends of studs 376 the heads of which are mounted for limited movement in guide bores 377 in anchor block 368 behind the punch block 369. Springs 378 tend constantly to force the plate 375 away from the punch block.

Also secured to the anchor block 368 by dowel pins 379 and cap screws 380 is a rivet flattening punch 381. This punch cooperates with a rivet flattening anvil 384 secured by dowels 385 and cap screws 386 to the die rest 387.

The die rest 387 is secured by cap screws 388 to the die holder 159. A lower punch block 389 is secured to the die rest by cap screws 390. The rivet piercing punches 391 are secured in the block 389. Recesses 392 are formed in the upper surface of the block 389 to receive the ends of 20 the positioning pins 371.

A strip guide plate 395 is rigidly secured to the ends of the studs 396. The heads of the studs are slidable in bores 397 formed in the die rest 387 behind the lower punch block 389. Springs 25 398 constantly tend to force the plate 395 upward.

The guide plate is provided with die holes 399 cooperating with the rivet turning punches 372 while the strip holding plate 375 is provided with 30 die holes 400 cooperating with the piercing punches 391.

Fig. 20 shows the parts retracted. In this position the positioning pins 371 and the rivet turning punches 372 are withdrawn back into the plate 375, the plate having been forced away from the punch block 369 by the springs 378. Likewise the strip guide plate 395 has been forced upward from the lower punch block 389 by the springs 398 until the rivet piercing punches 391 are withdrawn into the plate 395. Referring to 40 Fig. 21, the strip holding plate 375 has separated from the guide plate 395 sufficiently to allow freedom for forward movement of the strips. However, the separation is not sufficient to allow the 45 strips to get out of the guide plate. Here it is to be noted that the guide plate includes side guide ribs 401 held by cap screws 402.

When the press crosshead is moved down the plates 375, 395 are first brought together to clamp 50 the composite strip lightly; then the positioning pins 371 enter the coincident sprocket holes of the strip to position the same by a slight final movement; after this the plates and strip are forced downward to cause the rivet piercing 55 punches to pierce the rivet forming protuberances; and at about the same time, the rivet turning punches 372 and the rivet flattening punches 381 are brought into operation to perform their 60 respective actions on rivets which have already been moved forward.

Backlash at station #3 is taken up by mechanism like that used at station #1. Plungers 404 are at their upper ends driven into the punch holder 156 and are guided at their lower ends in bores 405 of the die holder 159. Springs 406 acting against the lower ends of the plungers support the weight of the crosshead and related parts. The reason for taking up the backlash on the downward stroke is similar to that prevailing for station #1—the press parts must be stopped accurately on the down stroke on account of the delicate work being done by the rivet turning punches and rivet flattening punches. Backlash take up is not needed at station #2 for there a simple through punching only is performed.

The operation may be readily followed by reference to Figs. 24 and 25. At station #1 the armor strips A1 and A2 are (after initial operations to punch sprocket holes in lengths long enough to reach the feeding device which then pulls them forward in successive increments of approximately sprocket hole lengths) accurately located by the positioning pins 250. These pins, 80

will be recalled, are mounted on a slide 257 which may be accurately set for different hole spacings to correspond to the actual spacings of the film strip upon which the armor strips are to be secured. The positioning pins act on the transverse edges of the sprocket holes. The strips are next clamped down securely in position by the clamp plates 286, after which the sprocket hole punches 251 and rivet protuberance punches 252 do their work. When the strips move forward the protuberances first fall in the recesses 276 and after the next move pass along the groove provided for them. The positioning pin 250 by being placed after the punch 251 always has sprocket holes to act upon. Also the protuberances 36 formed by the punches 252 are always at the same distance behind the sprocket holes.

At station #2 the film strip F passes under the plate 363, is positioned by the pins 345 and is punched by punches 347 to form rivet holes. The sprocket holes upon which the positioning pins act are of course, already formed in the film strip. The rivet hole punches 347 are the same distance from the positioning pins 345 as the punches 252 are behind the punches 251 at station #1. This insures that the rivet holes will always coincide with the rivet protuberances when the strips are assembled at station #3.

Between stations #1 and #3 the armor strips 105 A1 and A2 pass beneath station #2, being turned upside down and front for rear as they proceed.

Finally at station #3 the film strip is laid upon the armor strips with the rivet protuberances entering the rivet holes of the film strip. The 110 positioning pins 371 accurately place the strips. The upper plate 375 clamps the strips to the lower plate 395, after which both plates descend to impale the strips upon the piercing punches 391 which puncture the rivet protuberances so 115 that the hollow rivet walls formed thereby extend through the rivet holes in the film strip.

Upon further downward movement the punches 372 turn the burrs of the rivets and the bradding punches 381 flatten the turned rivet ends down 120 upon or into the film strip. 125

The objects and advantages are thus seen to have been supplied by the apparatus devised. The adjustments and settings may be quickly and conveniently made and when made indicate 130 accurately in what relationship the strips are being assembled. By this apparatus the armor and film strips are properly and securely fastened together without injury to either.

While one embodiment of the invention has 140 been described with particularity in order to furnish a tangible concept thereof, it will be understood that various changes and modifications may be made within the scope of the subjoined claims.

What I claim is:

1. Apparatus for armoring motion picture film strip, comprising in combination, a plurality of press shafts, a clutch-brake for each, a clutch shaft operating all of said press shafts, low speed 145 and high speed clutches on said clutch shaft,

- foot pedals which when pushed down engage the clutches and disengage the brakes of said clutch-brake devices, a foot pedal which when pushed down will operate all of said first-mentioned 5 pedals together, a foot pedal which when pushed down will disengage said low speed clutch and engage said high speed clutch, latch means for holding said pedals down, and a hand lever for releasing said pedals from said latches. 80
- 10 2. Apparatus for armoring film strip, comprising in combination, a press for performing an operation on an armor strip, a shaft for actuating said press, a press for performing an operation on a film strip, a shaft for operating said press, a press for performing an operation on the assembled composite strip, a shaft for operating said press, and a jack shaft geared to all of said shafts for operating them at the same speed. 85
- 15 3. Apparatus for armoring film strip, comprising in combination, a plurality of press shafts, a clutch-brake device for each, pedals for operating each of said clutch-brake devices separately, a pedal for operating all of said clutch-brake devices together, a latch for holding said last mentioned pedal, and means for releasing said latch. 90
- 20 4. Apparatus for armoring film strip, comprising in combination, a plurality of individual 30 presses for performing operations on the armor strip, film strip and composite film and armor strip respectively, separate shafts for each of said presses, a jack shaft turning all of said shafts, and clutches for said press shafts, having a single engaging position whereby the proper relative positions of said press shafts may be maintained. 95
- 25 5. Apparatus for armoring film strip, comprising in combination, means for punching sprocket 40 holes and rivet protuberances in armor strip, means for punching rivet holes in film strip, means for assembling said strips, piercing said protuberances to form hollow rivets extending through the rivet holes of said film strip, and bradding said rivets on said film strip, and means for coordinating and controlling all of said means. 100
- 30 6. Apparatus for armoring film strip, comprising in combination, means for feeding the armor strip, means for punching sprocket holes in the armor strip, pilot pins spaced from said punching means for piloting said strip accurately into proper position for punching after said feeding means has completed its action, said pilot pins 45 moving with the punching means, and means for varying the distance between said punching means and said pilot pins for varying the spacing between holes. 105
- 35 7. Apparatus for armoring film strip, comprising in combination, means for conditioning film strip and armor strip, means for moving said strips along separately but synchronously in unit increments of length to the conditioning means, and means for adjusting said conditioning means 50 to present different relative lengths of film and armor strip to each other in accordance with the shrinkage condition of the film strip, means for varying the action of the moving means in accordance with the shrinkage condition of said 55 film, and means for assembling the film and armor strips with the matched units of length placed together. 110
- 40 8. Apparatus for armoring film strip which comprises, means for feeding the strips forward by engagement with the front edges of the 60 sprocket holes, further means for accurately positioning the strips by engagement with the edges of the sprocket holes, and means for punching rivet elements on the strips at a fixed distance from the sprocket holes, whereby the rivet elements of the strips will accurately coincide regardless of any variation in the spacing between sprocket holes. 115
- 45 9. Apparatus for armoring film strip, comprising in combination, means for punching a strip, means including cooperating rolls for feeding the strip to the punching means, means for separating said feed rolls when the punching means operates on said strip, and means for permanently holding said rolls separated and inoperative when desired. 120
- 50 10. Apparatus for armoring film strip, comprising punch presses for forming rivet protuberances on the armor strip and turning the burrs of said rivets, and means for limiting the working stroke of said presses regardless of the backlash in the operating means therefor for the purposes set forth. 125
- 55 11. Apparatus as set forth in claim 10 in which said limiting means includes a spring acting against said presses. 130
- 60 12. Apparatus for armoring film strip, comprising in combination, opposed floating plates for guiding superposed film and armor strips, means bringing said plates together after the strips have been positioned for operation to clamp the strips between them and for subsequently moving both plates and the strips clamped between them as a unit to perform an operation upon the strips in cooperation with fixed means, and means which follow up said plates for performing another operation upon the strips. 135
- 65 13. The method of armoring film strip which comprises, punching sprocket holes and rivet protuberances in armor strip at one position, punching rivet holes in the film strip at a second position, and assembling the film and armor strip with the rivet protuberances of the armor strip disposed in the rivet holes of the film strip and the sprocket holes of the strips coinciding, piercing the rivet protuberances, turning the hollow rivets thus formed and flattening the rivets upon the strips at a third position, and conducting all of said operations simultaneously. 140
- 70 14. The method of armoring film strip which comprises, punching rivet protuberances in a metal armor strip by a punch acting downwardly, inverting the armor strip and placing it beneath the film strip with the protuberances disposed in rivet holes in the film strip, piercing the protuberances by a punch acting upwardly, and bradding the rivet by a punch acting downwardly, for the purposes set forth. 145
- 75 15. Apparatus for armoring film strip comprising in combination, means for feeding armor strip and film strip separately but in timed space-by-space relationship according to sprocket hole punchings, means to punch sprocket holes in the armor strip while it is separate from the film strip, means for adjusting the length of the spaces at which the armor strip is punched to make the spaces between holes correspond with the spaces of the film strip with which they are to be associated, and means to assemble and attach the film and armor strips with matched units of length coinciding and the sprocket holes of the armor and film strips in registry. 150
